RESET MEANS FOR HAND COUNTERS
Anton Van Veen, Canton Center, Conn.
Filed May 21, 1962, Ser. No. 196,184
3 Claims. (Cl. 235—144)

This invention relates to counters or tallies and more particularly to an improved resetting means for manually operated counters adapted for use singly or in groups.

A primary object of the invention is to provide rapid but simple resetting means for a single, hand-operated counter or for a group of aligned hand-operated counters which will prevent an overturn of the digit wheels during the resetting operation and will bring all digit wheels of a counter or group of counters simultaneously to their zero positions.

Another object of importance of the invention is to provide means to return the digit wheel supporting and resetting shaft to its initial position after this shaft has been rotated in a direction to reset all digit wheels of a counter or group of counters to their zero positions.

More specifically it is an object of the present invention to provide counters such as shown and described in my Patents No. 2,572,784 granted October 22, 1951, and No. 2,846,145 granted August 5, 1958, with the improved digit wheel resetting means forming the subject matter of the present invention.

With the above and other objects in view, the invention may include the features of construction and operation set forth in the following specification and illustrated in the accompanying drawing.

In the accompanying drawing annexed hereto and forming a part of this specification, I have shown the invention embodied in hand counters of the deep-notch type, but it will be understood that the drawing is not to be construed as defining or limiting the scope of the invention, the claims appended to this specification being relied upon for that purpose.

In the drawing:

FIG. 1 is a longitudinal sectional view of a hand-operated counter incorporating the present invention, the section being taken on the planes of the broken line 1—1 in FIG. 2, some of the digit wheels being shown in section;

FIG. 2 is a transverse section of the counter shown in FIG. 1, the section being taken on the plane of line 2—2 in FIG. 1;

FIG. 3 is a transverse section of a part of a counter taken on the plane of line 3—3 in FIG. 1;

FIG. 4 is a central longitudinal section of a counter generally similar to FIG. 1 showing a slightly different form of resetting return means; and

FIG. 5 is a perspective view of a group of aligned counters provided with the present invention.

In the above mentioned drawing, there has been shown but one embodiment of the invention, and a slight modification thereof, which are now deemed preferable, but it is to be understood that other changes and modifications may be made within the scope of the appended claims without departing from the spirit of the invention.

In the operation of counters of the manually operated type, it is usual to provide resetting means enabling the digit wheels of a single counter, or the digit wheels in each of a group of aligned counters, to be simultaneously brought to their zero indicating positions. This resetting is done in counters of the type disclosed by rotating the shaft, or shafts when a group of counters is to be reset, on which the digit wheels are rotatably mounted. In conventional counters of the type disclosed, the shaft or shafts may be rotated continuously so that much care must be taken not to overrun the zero positions of the

2

individual digit wheels. It is to positively prevent this overrunning of the several digit wheels in the counter or counters during a resetting operation that the mechanism hereinafter described has been devised.

- 5 Referring more particularly to the figures of the drawing, it will be seen that the counters comprise a body member or casing 10 within which a plurality of digit wheels 12 are mounted on a common shaft 14. Operation of a cover member 16 for the body member 10
10 actuates an arm 18 to rotate the several digit wheels 12 in the usual manner to effect tallying operation. As the above described members and their operation are similar to corresponding members in the above referred to patents, further description thereof is not deemed necessary.

The shaft 14 on which the digit wheels of the counter are individually rotatably mounted also forms the shaft for resetting the digit wheels to their zero positions. During the operation of the counter while effecting a
20 tallying operation, the reset shaft 14 for the digit wheels 12 does not rotate. When a tallying operation has been completed, the reset shaft 14 is rotated and in turn positively rotates the digit wheels 12 to their zero indicating positions. Rotation of this shaft 14 during a resetting operation is limited to slightly less than a single revolution to accomplish the objects of this invention. In one rotative position of the shaft 14, all digit wheels 12 of the counter, or group of counters, are aligned with their zeros in view. Beyond this predetermined position the
30 shaft 14 or shafts may not be rotated. This is for the reason that a radially outwardly extending projection 20 on a disk or collar 22 secured to or forming part of the shaft 14 abuts against a projection 24 formed within the casing 10. This position of shaft 14 is reached at the
35 conclusion of the resetting operation at which time each of the digit wheels is in its zero indicating position.

To facilitate successive resetting operations, provision is preferably made to return the shaft 14 or shafts to its or their initial positions while leaving the digit wheels
40 12 in their zero indicating positions. The shaft 14 or shafts therefore are in position to be again rotated in their resetting direction without first manually rotating them in a retrograde direction.

This means to return the shaft 14 or shafts to their
45 initial positions after a resetting operation may comprise a spiral spring 26 as shown in FIGS. 1, 3 and 4 formed preferably of wire or flat metal strip material. One end of the spring 26 is attached to a shaft 14 and the opposite end suitably attached to the casing 10 as shown at 28.
50 Normally the spring maintains the shaft 14 with the projection 20 formed on its collar 22 against one side of the stop 24 provided within the casing 10. From this position the shaft 14 may be rotated manually until the projection 20 on the collar 22 abuts against the opposite side
55 of the stop 24 on the casing 10 by which rotation the resetting operation is completed and each wheel then will be in its zero indicating position.

During this resetting operation, rotation of the shaft 14 in the direction indicated by the arrow in FIG. 2 successively picks up the individual digit wheels which have been moved from their zero positions during the previous tallying operation as described in the above mentioned patents. When the shaft 14 has been rotated in its resetting direction to engage its projection 20 with the stop 24 on the casing 10, all wheels that have been moved from their zero position will have been picked up by the engagement of their spring ends 30 with a recessed portion 32 of the shaft 14.

To actuate the reset shaft 14 of a counter to reset the digit wheels 12 to their zero indicating positions, the shaft 14 may be provided with an axial non-circular opening 34 through which may extend a correspondingly

shaped rod 36 having a knob 38 on its outer end for manual operation. As shown in FIGS. 1 and 4, the inner portion of the rod 36 may be materially reduced in cross section to make it flexible and resilient. At its extreme inner end an extension 40 may be formed so that when in place this inner end will snap over the end of the reset shaft 14 and retain the operative parts of the counter and itself in place.

When counters are used in multiple aligned arrangement, a single collar 22 and projection 20 only may be employed on the shaft 14 of but one counter to effect resetting the digit wheels of all counters of the group.

In multiple aligned arrangements of counters it is desirable to simultaneously reset the wheels 12 of all counters of the group simultaneously. For this purpose a rod 42 of non-circular cross-section is passed through the shafts 14 of each counter of the group, as shown in FIG. 5. The shaft 14 of each counter when this is done must be in the same rotative position, that is the notch 32 of all shafts 14 must be in alignment. By means of a knob 44 attached to the rod 42 at one end, the rod may be manually rotated to effect the resetting operation of all counters of the group. The shafts 14 of each counter of a group are always maintained in identical angular position; that is, when the resetting operation is completed each counter is brought to its zero indicating position and further rotation of the rod 42 is prevented by a projection 20 on at least one of the shafts 14 of the counters of the group abutting against a projection 24 formed or provided on the casing thereof.

FIG. 4 shows a slight modification of the counter shown in FIGS. 1 and 3. In this figure the spring 26 for returning the shaft 14 is mounted on the outside of the casing and the projection 20 on the shaft 14 engages against a pin 46 extending inward from one of the end walls of the casing 10.

I claim as my invention:

1. A resetting device for manually-operated counters, comprising a casing, a plurality of coaxially mounted digit wheels therein, a rotatable shaft on which said wheels are mounted for independent rotation, a ratchet connec-

tion between each wheel and said shaft to effect resetting operations, stop means to limit rotation of said shaft in one direction to a fixed position in which all wheels are rotated to indicate the same digit, and a helical spring surrounding said shaft and having its ends attached respectively to said casing and shaft to return said shaft to its initial position.

2. A resetting device for manually-operated counters, comprising a casing, a plurality of coaxially mounted digit wheels therein, a rotatable shaft on which said wheels are mounted for independent rotation, a ratchet connection between each wheel and said shaft to effect resetting operations, a projection on said shaft engaging a stop in the wall of said casing to limit rotation of said shaft to a fixed position in one direction, and a helical spring having its ends respectively attached to said shaft and said casing to return said shaft to its initial position.

3. A resetting device for manually-operated counters, comprising a casing, a plurality of coaxially mounted digit wheels therein, a rotatable shaft on which said wheels are mounted for independent rotation, a ratchet connection between each wheel and said shaft to effect resetting operations, spring means engaging a longitudinal notch in said shaft to limit rotation of said shaft to a fixed position in one direction in which position all wheels indicate the same digit, and a helical spring surrounding said shaft having one end attached to said shaft and the other end attached to said casing to return said shaft to its initial position.
